CLAIM

The ornamental design for an air pump for blood pressure cuff, as shown and described.

DESCRIPTION

FIG. 1 is a front isometric view of my new design for an air pump for blood pressure cuff;

FIG. 2 is a rear isometric view thereof;

FIG. 3 is a front view thereof;

FIG. 4 is a rear view thereof;

FIG. 5 is a right side view thereof

FIG. 6 is a left side view thereof;

FIG. 7 is a top view thereof; and,

FIG. 8 is a bottom view thereof.

The portion indicated in phantom forms no part of the design.
